UNITED STATES PATENT OFFICE.

BASCUM LENTON STRANGE, OF HERNANDO, FLORIDA.

STOVEPIPE-CLAMP.

1,378,143.

Specification of Letters Patent. Patented May 17, 1921.

Application filed April 26, 1920. Serial No. 376,716.

To all whom it may concern:

Be it known that I, BASCUM LENTON STRANGE, a citizen of the United States, residing at Hernando, in the county of Citrus 5 and State of Florida, have invented certain new and useful Improvements in Stovepipe-Clamps, of which the following is a specification, reference being had to the accompanying drawings.

10 This invention relates to an improved combined stove pipe clamp and coupling and its object is to provide a device of this kind which is very simple, efficient and practical in construction and capable of being cheaply made and sold at a reasonable profit.

Another object is the provision of a clamp, which is capable of being stamped and formed from a single piece of sheet 20 metal in one operation of a die, or one operation of a drop forge method.

Another object is to provide a clamp in the form of a band, which is provided with free ends adapted to connect when the 25 band is engaged about the stove pipe, and provided with upper and lower over-turned flanges or parts to be engaged by the two sections of stove pipe to be joined and clamped together, thereby preventing the 30 downward movement of the upper section and upward of the lower section, in fact prevent relative movement of either section.

While the design and construction at 35 present illustrated and set forth is deemed preferable, it is obvious that as a result of a reduction of the invention to a more practical form for commercial purposes, the invention may be susceptible to changes, 40 and the right to these changes is claimed, provided they are comprehended within the scope of what is claimed.

The invention comprises further features and combination of parts, as will be hereinafter set forth, shown in the drawings and claimed.

In the drawings:—

Figure 1 is a view in elevation showing the improved combined clamp and coupling 50 as applied to adjacent stove pipe sections, showing the clamp wherein the ends are joined,

Fig. 2 is a vertical sectional view through the two stove pipe sections showing the 55 clamp in position.

Fig. 3 is a cross sectional view on line 3—3 of Fig. 2 showing the manner of connecting the ends of the clamp,

Fig. 4 is a detail sectional view on line 4—4 of Fig. 2; and

Fig. 5 is a detail perspective view of the two ends of the combined coupling and clamp.

Referring to the drawings, 1 designates the upper section of a stove pipe and 2 the lower section. In practice the upper section telescopes over the lower section, and in order to prevent relative movement of the two sections, an improved combined clamp and coupling is provided. This 70 combined clamp and coupling 3 is constructed from a single piece of sheet metal in circular outline, and the upper portion of the band is over and in-turned, thereby forming an abutment flange 4. In fact the 75 lower marginal portion of this abutment flange is flared as shown at 5 against which the upper marginal edge of the lower pipe section abuts, thereby preventing movement of the lower pipe section in an upward 80 direction.

The lower portion of the band or clamp or coupling is outwardly and upwardly turned, the fold thereof being designated by the character 6, thereby providing an 85 abutment flange 7. The upper marginal edge of this flange is flared outwardly as shown at 8 in order to provide a shoulder against which the lower marginal edge of the upper pipe section abuts thereby preventing relative downward movement of 90 said section.

Adjacent the ends of the combined coupling and clamp, the ends of the inwardly, downwardly and outwardly and upwardly 95 turned flanges terminate in lateral portions 9 and 10, which abut. In other words, the lateral portions 9 abut each other, while the lateral portions 10 likewise abut, thereby holding the band or clamp in position 100 and conforming to the pipe sections. These lateral portions also serve as additional abutment means for the marginal edges of the pipe sections, thereby additionally preventing relative movement of the pipe sections. In order to permit these lateral portions to abut for the above purposes, the ends of the band or clamp slightly overlap as shown in the detail transverse sectional view, Fig. 3.

The invention having been set forth, what is claimed as new and useful is:—

1. In a device as set forth, a pair of adjacent pipe sections, a combined clamp and coupling therefor comprising a band telescoping respectively within one section and over the other section, the circular marginal edges of the band having inwardly and downwardly, and outwardly and upwardly turned flanges, the marginal edges of which being flared and adapted to be engaged by the respective marginal edges of the pipe sections, thereby preventing relative movement of the pipe sections, the ends of said flanges terminating in laterally disposed parts extending inwardly and outwardly, thereby constituting additional means against which the pipe sections abut to assure prevention of relative movement of the pipe sections, the ends of the band being overlapped, and said lateral parts additionally serving to hold the band in uniformity with the pipe sections.
2. As an article of manufacture, a combined clamp and coupling comprising a sheet metal band adapted to telescope respectively within and over adjacent ends of a pair of pipe sections, the opposite marginal portions of the band having respectively inwardly and downwardly, and outwardly and upwardly disposed flanges, the marginal edges of said flanges being inwardly and outwardly turned against which the marginal edges of the pipe sections are adapted to abut to prevent relative movement thereof, the ends of the band adapted to overlap, the ends of the flanges having means which to-

gether with the overlapping ends of the band act to hold the band conforming to and engaging the pipe sections.

3. As an article of manufacture, a combined clamp and coupling comprising a sheet metal band adapted to telescope respectively within and over adjacent ends of a pair of pipe sections and provided with separable ends, the opposite marginal portions of the band having respectively inwardly and downwardly, and outwardly and upwardly annular abutment means to be engaged by the respective marginal edges of said pipe sections to prevent relative movement, the construction and arrangement of the separable ends and the ends of the abutment means being such as to act to hold the band conforming to and engaging the pipe sections.

4. As an article of manufacture, a combined clamp and coupling comprising a sheet metal band adapted to telescope respectively within and over the adjacent ends of a pair of pipe sections, the opposite marginal portions of the band having respectively inwardly and downwardly, and outwardly and upwardly disposed flanges, the respective marginal edges of said flanges being inwardly and outwardly turned against which the marginal edges of the pipe sections are adapted to abut to prevent relative movement of the sections, and to permit pipe sections of relatively different diameters to be united.

In testimony whereof I hereunto affix my signature.

BASCUM LENTON STRANGE.
